OPERATION OF DRUM TYPE MATERIAL
REDUCTION MILLS EMPLOYING BALL
CHARGES

David Weston, Toronto, Ontario, Canada

Application July 2, 1951, Serial No. 234,782

Claims priority, application Canada May 15, 1951

6 Claims. (Cl. 241—19)

1

This invention relates to the comminution of materials in material reduction mills employing a ball charge and more particularly it relates to the use of a novel ball charge in combination with a mill which is provided with a plurality of highly upstanding circumferentially spaced apart crusher bars as will be described in more detail hereinafter.

Heretofore in the operation of ball mills it has been the general practice to employ what has been referred to as a "seasoned" ball charge; that is to say, a ball charge which is made up of individual balls of varying diameters. In operation, the balls are gradually reduced in size due to wear until they pass out of the mill in the normal course of operations when they are reduced to a size commensurate with the particle size of the product of the mill. Large balls are added from time to time during operation of the mill in order to maintain a so-called "seasoned charge." Such charges have seldom been used in cylindrical types of mill under a charge volume of 35% and the volume occupied by the ball charge is frequently as high as 50% of the mill volume (including voids), the capacity of the mill generally increasing proportionately with the increase in volume of the ball charge up to this latter figure. According to this current practice, the normal total volume occupied by the material undergoing comminution and the ball charge is of the order of from about 45% to about 50% of the mill volume and the proportion of balls in the charge of any given diameter is generally dependent upon the size of the feed. In current practice, the angle of "nip" between two balls basically determines the size of feed particle which will be efficiently reduced and thus the size of the ball required to give efficient results will normally be determined by the particle size of the feed. The comminution of materials in ball mills employing the above described prior practices is described in some detail by Taggart (Handbook of Mineral Dressing, 3rd edit., 1948).

In contradistinction to the above described prior practices, my invention contemplates the use of a relatively small ball charge composed of relatively large diameter balls, the ball charge occupying a maximum of 3% of the volume of the mill exclusive of voids and the combined volume of the ball charge and material charge being not more than a maximum of about 32% of the volume of the mill.

2

This novel type of ball charge is used according to the invention in combination with a mill which is provided with highly upstanding crusher bars which are fairly widely circumferentially spaced apart around the interior of the cylindrical wall of the drum. While the invention contemplates generally the use of any mill which is thus provided with highly upstanding crusher bars, it affords particularly good results in connection with mills of the kind described in my co-pending applications Numbers 175,353, filed July 22, 1950, and 749,131, filed May 20, 1947, the latter maturing into Patent 2,555,171, and will for convenience be described in conjunction with this type of mill. Thus, although the present invention has a broader application, it is preferred to use it in connection with mills of the type described in my said prior applications, in which mills the diameter of the drum is at least twice the length thereof.

The type of mill to which this invention has particular application generally comprises a drum arranged for rotation in a substantially vertical plane, said drum having two end walls and a cylindrical wall, which latter is provided with a plurality of highly upstanding circumferentially spaced apart crusher bars mounted around the interior thereof. Inlet and outlet ports for the charging of feed material and withdrawing of comminuted material are provided in false trunnions about which the drum is rotated. Feed is generally fed to the mill through the inlet port by gravity and the mill is kept clean by a current of air which is drawn across the mill through the inlet port and out the outlet port, which current of air on passing through the mill entrains the finely divided product of the mill and carries it through the outlet port where it is passed through a classifier which separates the heavier oversize particles from the stream, the oversize being allowed to flow back into the mill through the outlet port. The above type of mill is becoming well known and is used in various embodiments fairly widely throughout the art. For convenience of reference such type of mill will herein-after be referred to as "a mill of the type described."

The present invention provides a method of operating a mill of the type described which comprises; maintaining within the drum a ball charge consisting essentially of large balls occupying at least about 0.35% but not more than

about 3% of the total mill volume exclusive of voids; maintaining the total charge in the mill at from about 20% to about 32% of the mill volume inclusive of voids, and rotating the drum at a speed between about 84% and about 90% of its critical speed. The critical speed in R. P. M. of a mill of this type is generally accepted as being

$$\frac{54.19}{\sqrt{R}}$$

where R is the internal radius of the drum in feet between opposing crusher bar faces. It is the speed at which a particle of material of 3" diameter or smaller within the mill will be carried completely around the mill without falling away from the face of the crusher bars, or for all intents and purposes from the periphery, the centrifugal force at speeds greater than the critical speed being sufficient to hold these particles firmly against the cylindrical wall of the drum at all times.

The invention also provides a novel ball charge, in combination with a mill of the type described, which ball charge consists of a relatively small number of large balls. According to the invention, the ball charge consists of at least ten balls which occupy at least about 0.35% but not more than about 3% of the mill volume exclusive of voids. The ball charge of the invention consists essentially of balls weighing more than four pounds and having a diameter of more than about three inches. Preferably according to the invention, the diameter of the balls is about five inches.

The invention and the theory upon which it is based will be described, in greater detail in the following specification in which reference is had to the accompanying drawings, in which:

Figure 1 is a vertical cross-section of a charged drum in a mill of the type described to which feed is being supplied, illustrating the paths which will be followed by balls of varying diameters when the drum is rotated at a speed within the range of from about 84% to 90% of critical;

Figure 2 is a cross-section similar to that shown in Figure 1 illustrating the path followed by the balls of a ball charge according to the invention when the mill is operated according to the method of the present invention;

Figure 3 is a further cross-section similar to that shown in Figure 1 but illustrating what takes place when the total charge within the drum is permitted to exceed the maximum according to the method of the present invention.

Referring now more particularly to the drawings, it will be seen from Figure 1 that generally speaking the smaller the diameter of the balls in the ball charge, the further they will be carried upwardly by the drum before the force of gravity overcomes the centrifugal force which is holding them against the periphery thereof. The reason for this is that the centre of gravity of a small ball will be closer to the cylindrical wall of the drum than will be the centre of gravity of a large ball and, accordingly, the moment arm of the small balls will be greater and centrifugal force holding them to the periphery of the drum will be greater. Accordingly, the interior of the drum may be theoretically divided into zones; there will be the cataracting zone in which balls of, for instance, $\frac{1}{2}$ " to $\frac{3}{4}$ " in diameter, will be falling freely from a point near the top of the drum to strike the descending side of the cylindrical wall of the drum near the bottom with free fall impact; there will be a cascading zone where balls

of 3" diameter and larger will be rolling down or cascading over the top of the charge eventually to move vertically towards the periphery of the drum near the bottom thereof; and there will be an abrasion zone within the charge near the upwardly moving side of the cylindrical wall of the drum.

If the mill is operated at between 84% to 90% of the critical speed with a total charge of 20% to 32% of the mill volume including voids, the charge itself will assume a position against the upwardly moving side of the cylindrical wall of the drum with the toe of the charge being situated approximately astride a line drawn vertically through the axis of the drum, with a "false" toe of feed material extending slightly past said line. It will be seen moreover, that the path followed by the balls of generally 3" in diameter and over will as they cascade down through the cascade zone cause them to approach the cylindrical wall of the drum substantially vertically substantially between the "true" toe and the "false" toe of the charge.

When the mill is operating in accordance with the method of the invention and the ball charge consists essentially of balls of relatively large diameter, preferably of a diameter of about 5", all of the balls in the charge will follow the same general path which will be generally curved, substantially as illustrated in Figure 2. In fact, it might be considered that the ball charge behaves as if groups of the balls were strung together in a number of chains lying parallel to each other along the length of the mill and continuously rotating in the direction of the arrows around the path illustrated in Figure 2. It will be seen, moreover, from Figure 2 that the balls descend into the toe of the charge at a point adjacent the bottom of the mill at which point the radial centrifugal force produced by rotation of the mill and the force of gravity are acting together. Each ball thus entering the toe of the charge will, accordingly, have a high degree of inertia. As each crusher bar enters the "false" toe of the charge, the material in the toe between the crusher bar and a ball of the ball charge which is entering the toe in the manner aforesaid will be crushed between the crusher bar and the ball. The crushing action is similar to the action of a jaw crusher and the crusher bar may be considered the moving jaw and the ball of the ball charge may be considered to be the stationary jaw. During periods when no feed is being supplied to the mill, and there is therefore no "false" toe, the crushing action results from the balls being driven into the true toe of the charge by the crusher bars.

In accordance with the foregoing, it will be appreciated that theoretically there should be a sufficient number of balls present in the charge to form a series of "chains" around which the balls are spaced with sufficient density that series of balls are arriving in the toe of the charge at about the same rate as crusher bars are entering the toe of the charge. It will further be appreciated that since the principal effectiveness of the balls in a charge according to my invention is as inertia bodies acting in concert with the crushing bars to crush the material in the crushing zone, the balls during their travel around the generally curved course will be merely occupying space which could be occupied by feed material. It is, therefore, desirable according to the invention to have the length of the path of the balls as short as possible. This can be accomplished very sim-

ply by arranging to have the charge consist essentially of large balls. As the balls become reduced in size due to wear during operation of the mill, they will progressively travel further and further in their generally curved course and it is desirable at intervals to eliminate from the mill balls of a diameter of less than about 3". It may, however, in some instances be desirable to retain a small number of balls of under one inch in diameter because of the work which may be done by these balls in free fall impact on the particles of charge which are also falling through the cataracting zone of the mill.

Although the specific gravity of the balls apparently has no appreciable effect upon the path that a ball of any given diameter will follow during operation of the mill, it will, of course, be appreciated that the effectiveness of a ball as an inertia body in the crushing zone will be increased if the ball is made heavier. It is, accordingly, preferred according to the invention to form the balls of the ball charge from a material having a high specific gravity. Tungsten carbide compositions, which have a specific gravity of approximately 14 and are immensely hard, are ideal substances from which to form ball charges according to the invention. Unfortunately, due to material shortages and high cost, tungsten carbide is not always available at a cost which would enable its economical use and, consequently, the balls will generally be formed from alloy steel of one sort or another.

Generally speaking, any ball which has a diameter of about 3" or more and a weight of about four pounds or more will be useful in accordance with the invention as an inertia body and, accordingly, in carrying out the method of the invention it is essential to ensure that the charge consist essentially of balls meeting these specifications. It has been found, moreover, that a minimum of ten balls is generally required to assure the formation of the so-called "chains" and effectively produce a continual crushing action of the character described above. In mills of from five to nine feet in diameter, I have found that about five inches in diameter is a practical maximum limit for the size of individual balls making up the charge. In larger mills, larger balls may be used. It should be remembered, however, that as the size of the mill increases the crushing force exerted by each ball also increases and the forces exerted by the balls reach tremendous proportions. A six inch iron ball which would weigh about 32 pounds in an 18-foot mill where the peripheral speed would be about 14 feet per second, when operating within the range of speeds prescribed according to the invention, would place a force on the crusher bars capable of exceeding the permissible stress of the material from which these are made, unless special precautions are taken to increase their strength. There does not appear, however, in theory to be any upper limit within the limit of present practical considerations for the sizes of the balls in the ball charge provided a sufficiently strong construction of the drum and crusher bars is provided for and, accordingly, it may be stated that as long as there are at least ten balls in the charge and the total volume of the ball charge does not exceed the maximum set forth, the method of the invention will operate to produce the increase in efficiency indicated by the results of the examples hereinafter set forth.

First of all, the mill must be rotated at a speed of from 84% to 90% of the critical speed in order that the toe of the charge be situated substantially astride a vertical line drawn through the axis of rotation of the drum and the balls be delivered in appropriate positions to take part in the desired crushing action in the crushing zone. Secondly, the balls in the ball charge must be of an appropriate size as set forth and in appropriate quantity to concentrate in the toe of the charge in the manner set forth. Of course, once sufficient balls are present to provide for the carrying out of the crushing action in an efficient manner, it is undesirable to increase the size of the ball charge further because this will decrease the available volume within the mill for the material being reduced and seriously increase the ball wear due to balls abrading on one another. The third critical factor in the method of the present invention is in the total volume of charge within the mill. This should take up at least 20% of the volume of the mill including voids within the charge, but should not take up more than 32% of the volume of the mill including voids. It has been found that the efficiency of the mill drops off markedly if the total volume of charge exceeds 32%. The reason for this is apparent from a consideration of Figure 3. If the total volume of charge becomes too large then, even at the high speed of operation according to the present invention, the toe of the charge extends over past the vertical line drawn through the axis of rotation of the drum in the manner illustrated in Figure 3 and balls which are cascading through the cascade zone do not approach the periphery of the drum in a substantially vertical direction and, consequently, are incapable of cooperating with the crusher bars to act as efficient inertia bodies in the manner set forth. Generally speaking, I have found that optimum results are achieved if in following the process of the invention the charge volume including voids is maintained at approximately 27% of the mill volume.

The remarkable increase in efficiency provided by the process of the present invention and the novel ball charge thereof acting in conjunction with the crusher bars of a mill of the type described is illustrated by the following data compiled from the operation of a pilot mill with nominal dimensions of two feet in length and five feet in diameter. The data in the following examples is illustrative of the application of the invention to the reduction of three general types of material, namely friable material, medium-tough material and tough material. The results achieved illustrate the advantages of the invention and demonstrate the increase in effectiveness of the crushing action obtained when operating in accordance with the invention. In the case of friable material, for instance, which is very readily broken down, as would be expected, the use of the invention does not increase the capacity of the mill. In that case the advantages derived arise as a result of the quick initial breakdown of the feed material in the crushing zone permitting more work to be done on the individual broken down particles in the abrasion zone to produce a final product within the desired range of particle size which has improved metallurgical characteristics. As would be expected, however, in the reduction of medium-tough material and tough material, the increase in efficiency of the crushing action obtained results in a pronounced increase in the capacity of the mill.

7
EXAMPLE 1*Friable material*

The following table of results was compiled from the operation of the pilot mill using as feed loosely bonded sandstone:

Conditions of Pilot Mill Run			Screen Analysis Product		Chemical Analysis		
Ball Charge	Max. Feed Rate lbs./hr.	Manometer Reading, ins.	-20	-28	SiO ₂		Fe ₂ O ₃
			+100	+150	Head Prod.	Head Prod.	
None	900	5	79.3	83.7	98.65	99.21	0.32
12 5/8" Dia. Steel Balls	900	5	78.9	83.8	98.65	99.30	0.32
							0.10

NOTE.—Percent volume of mill occupied by ball charge 1.0%.

In this case the feed material being loosely bonded sandstone, is very friable and it is accordingly to be noted that there is no overall increase in capacity brought about by the use of a ball charge in accordance with the invention. From a metallurgical point of view, however, it is noteworthy that there is a considerable reduction of iron oxide content of the product of requisite grain size representing in all about a 28 1/2% improvement. In the material treated, the iron oxide occurred chiefly as a finely bonded coating to the silica particles. In breaking down the feed material quickly by means of the enhanced crushing action using a ball charge according to the invention the abrasion action in the abrasion zone is permitted to work on the individual particles for a longer length of time and the result, as exemplified above, is that a cleaner product is produced. The sandstone used as a feed in this example was intended for use in the manufacture of glass and, as is well known, the presence of iron oxide in glass sand is exceedingly deleterious and each 0.01% of iron oxide in a product lowers the grade of the glass sand and materially increases the cost of purification in the subsequent glass manufacturing process.

EXAMPLE 2

Medium-tough material

A medium-tough quartzite was used as feed material to the pilot mill, giving the following results:

Conditions of Pilot Mill Run			Screen Analysis Product, -20+100
Ball Charge	Max. Feed Rate lbs./hr.	Manometer Reading, ins.	
None	636	9.4	56.5
12 5/8" Dia. Steel Balls	840	9.4	57.5

NOTE.—Percent of mill volume occupied by inertia media charge 1.0%.

The quartzite treated in this pilot mill run is considered a medium-tough material to crush and grind. It will be noted that as in the friable material the screen analysis of the product can be considered approximately the same. However, the output, with a very small percentage of inertia bodies, was increased by approximately 32%.

8
EXAMPLE 3
Tough material

Gold-bearing porphyry ore was used as feed to the pilot mill and the following results were obtained:

Conditions of Pilot Mill Run			Screen Analysis Products, -200	Percent of Mill Volume Occupied by Inertia Media Charge
Ball Charge	Max. Feed Rate lbs./hr.	Manometer Reading		
None	440	7.0	39.3	0.00
10 5/8" Dia. Steel Balls, Total Weight 180 lbs.	850	7.0	31.9	0.83
45 3/8" Dia. Steel Balls, Total Weight 180 lbs.	720	7.0	26.9	0.82
12 3/8" Dia. Tungsten Carbide Balls, Total wt. 168 lbs.	985	7.0	43.0	0.41

NOTE:
Weight of 5-inch dia. steel ball 18.0
Weight of 3-inch dia. steel ball 4.0
Weight of 3.7-inch dia. tungsten Carbide Ball 14.0

This material is considered as one of the toughest materials to crush and grind. It is noteworthy that the use of inertia bodies according to the invention does not necessarily result in a greater proportion of the product being within the -200 screen analysis size range. The reason for this is that, using no ball charge the crushing action obtained has a low efficiency so that a large amount of grinding takes place by abrasion between comparatively large solid surfaces. This accounts for the fineness of grind obtained without the use of a ball charge.

The great increase in the crushing efficiency brought about by the presence of the ball charge according to the invention quickly reduces the large size particles of feed and produces a much greater range of particle sizes within the range where the air stream will remove them, the result being a much higher overall capacity with a smaller percentage of the product being within the -200 screen analysis size range. Measured in terms of surface area produced per unit of time the increase in capacity is remarkable.

It will be noted, moreover, in comparing the use of 5 inch steel balls with the use of 3 inch steel balls, that the 5 inch balls produce a better result both as regards capacity of the mill and as regards screen analysis of the products.

Finally, the greater crushing effect obtained with the heavy density tungsten carbide balls is clearly illustrated in the results recorded.

From the above examples of operation on a pilot mill scale it will be apparent that the present invention brings about a considerable increase in capacity when applied to the reduction of materials classified as medium-tough or tough. Furthermore, even in the case of friable materials it is apparent that, although no increase in mill capacity may be obtained, the use of the invention may bring about an improved metallurgical result, the improvement in this respect depending upon the nature of the particular material being reduced and the characteristics of the product considered desirable in the subsequent treatment of such material.

While the above tests were conducted using a ball charge consisting of balls which were essentially spherical in shape, these being the preferred form of reduction media, it will be appreciated that the present invention contemplates the use of any of the well known shapes of reduction media and accordingly it is to be under-

stood that whenever I refer herein to a "ball" or to a "ball charge," I intend to include any of the usual reduction media.

The embodiments of the invention in which an exclusive property or privilege is claimed are defined as follows:

1. A method of operating a material reduction mill of the type described employing a ball charge, said mill including a drum arranged for rotation in a vertical plane and having a cylindrical wall and two end walls, said drum being provided with a plurality of highly upstanding, circumferentially spaced apart crusher bars secured to the interior of the cylindrical wall thereof, which method comprises; maintaining within the drum a ball charge containing at least ten balls and consisting essentially of balls having a diameter of more than about three inches, and weighing at least four pounds each, said ball charge occupying at least about 0.35%, but not more than about 3% of the mill volume exclusive of voids; maintaining the total charge in the mill at from about 20% to about 32% of the mill volume inclusive of voids; and rotating the drum at a speed between about 84% and about 90% of its critical speed, whereby said balls tend to concentrate as inertia bodies in the toe of the charge and act in cooperation with said crusher bars to produce a highly efficient crushing action.

2. The method as defined in claim 1, in which

the total charge in the mill is maintained at about 27% of the mill volume inclusive of voids.

3. The method as defined in claim 1, in which the mill has an internal diameter of from about 5 to about 9 feet and a ball charge is maintained which consists essentially of balls having a diameter of about 5 inches.

4. The method defined in claim 1 applied to a mill having a drum the diameter of which is at least twice the length thereof.

5. The method defined in claim 2 applied to a mill having a drum the diameter of which is at least twice the length thereof.

6. The method defined in claim 3 applied to a mill having a drum the diameter of which is at least twice the length thereof.
